UNITED STATES PATENT OFFICE.

GEORGE KELLOG, OF NEW YORK, N. Y.

DETACHABLE BUTTON.

Application filed December 8, 1925. Serial No. 74,151.

This invention relates to buttons and in particular to a type which can be securely attached to a garment or piece of material without the use of thread or other like holding agent.

A particular object of the invention is to provide a detachable button, for garments or the like, which can readily be applied at any time, said button being in the nature of a bachelor button and being arranged so that its attachment to the garment does not necessitate the forming of a button hole in the garment prior to the application of the button thereto.

15 A further object of the invention is to provide a button comprised of a central link portion which will bind the button securely to the garment and which will also firmly hold the button so that the same can not be torn out of the garment in which it is attached, there being provided in connection with said link, a backing plate which is disposed on the opposite side of the garment from the button and which strengthens the 20 material adjacent the button so that the latter cannot be torn out of the material.

25 A further object of the invention is to provide a garment piercing member as a part of the combination button which can be forced through the material to be engaged by a link member to which can be attached the button itself, the whole, when assembled giving the appearance of a sewn button and also providing room for the material that is buttoned over the button.

Referring to the drawings wherein I have shown a preferred embodiment of my invention,

Figure 1 is a view in section through a 40 piece of material having applied thereto my improved button.

Figure 2 is an enlarged cross-sectional view of the button assembled showing how the same would appear when attached to the goods.

Figure 3 is a composite view showing the three parts of the button, namely, the button itself, the link and the stud.

50 Figure 4 is a view similar to Figure 2 showing a slightly modified form of link, the same being adapted for use with larger buttons than of the type illustrated in Figure 2, and

Figure 5 is a composite view similar to Figure 3 showing the three parts of the button adapted for use on thin material or in small garments, such for instance, as linen wear.

Referring to the drawings in detail, 5 indicates a stud member, the upper portion of which is pointed as at 6 to provide a material piercing point, the central portion of the stud being threaded as at 7 and being reduced in its lower portion as at 8 which joins said stud with the stud plate 9. The 65 stud plate 9 and the stud are preferably made of metal although any other suitable material such as bone may be used and the stud plate 9 is provided adjacent its outer edges or periphery with the upstanding prongs 10 which are in the nature of needle points and which are adapted to pierce the goods and hold the stud plate 9 from revolving when a link member is applied to the stud 5.

The link member comprises the disc portion 11, the outer periphery of which is knurled as at 12 and which forms the base for the intermediate threaded portion 13, there being disposed above said intermediate portion 13, the spherical part 14 which is also knurled for convenience in turning said link down over the stud 5 as shown in Figure 2. As will be noted in said figure, the link is provided with a bore which is threaded to match the threads of the stud 5, the internal end of the bore being pointed and extending into said spherical end portion 14 to provide room for the tip end of said stud 5. It will be evident that by enlarging the spherical portion 14 that a longer pointed tip 6 can be provided on the stud member 5 for piercing heavy material where a sharp, long point is desired. It will also be noted that the disc portion 7 of the link 85 is the same diameter, substantially, as the stud plate 9.

It is evident upon inspection of Figures 2 and 4 that the reduced portion of the stud 5 allows the expansion of the material after the threaded portion of the stud has passed therethrough and allows the same to be flattened between the stud plate 9 and the disc portion 11 of the link above referred to so that distortion of the garment adjacent the button is eliminated and the link member

can be threaded down over the stud 5 tightly against the material to cause the prongs 10 of the stud plate 9 to securely engage the goods, so that the goods adjacent the button 5 is firmly gripped throughout the area of the stud plate 9 and danger of pulling the button out of the goods is eliminated.

In Figure 4 I have shown a slight modification to the link member which consists 10 in providing a flat dome 15 which is adapted for use in the large type of button. The button used may be of any suitable material and may be formed with a bead edge 17, the button itself being indicated at 16 and 15 being provided with a central, threaded bore 18 into which the threaded portion 13 of the link is engaged, when the button is threaded in place on said link. The button is knurled on its outer periphery as at 19 so that the same can be securely threaded 20 into place over the link member. It will be noted that the bottom diameter of the button is substantially the same diameter as the disc portion 11 of the link so that 25 when the button is in place, it would appear as though the link member is a solid part thereof and the link disc 11 serves the purpose of holding the button in spaced relation with the material so that the garment portion that is buttoned over the button will be substantially held thereby without wrinkling or distortion.

In Figure 5 I have shown a small form 30 of the button as illustrated in Figure 2 and 35 in which the button member 16 and the link member are substantially the same but the stud member 9 or stud plate is provided with the knurled edge 20 and the top of said member is provided without the prongs 10 shown in the construction mentioned. It is 40 evident that the stud plate 9 in all instances can be knurled so that a firm grip may be had thereon when the link member is being threaded to the stud portion thereof.

45 It is evident therefore that I have provided an improved button comprising a minimum number of parts, the intermediate portion of which provides a spacing member and also a flanged portion which maintains 50 the goods in flat position adjacent the button and which also securely attaches said button to the garment.

55 It will also be seen that I have provided a button which will not easily tear out of the goods and one which will not become loose and unsightly, it being of course understood that the surface of the button itself may be suitably decorated and the button and other parts associated therewith may be made of any suitable material and polished or decorated to provide a pleasing appearance.

60 It will be particularly noted that the disc portion of the link is substantially the same diameter as the plate portion of

the stud so that the goods is held firmly therebetween and is not wrinkled as is the case with buttons using a larger or smaller plate member, which causes bulging of the goods at the exterior edges of said plate member.

While I have shown and described a particular form of my invention, it is to be understood that changes may be made therein within the scope of the appended claims. 75

Having described my invention what I claim as new is:—

1. A detachable button for garments or the like comprising a piercing stud member having a central threaded portion, a link member in threaded association therewith, a button having a central opening therein removably associated with said link member, a disc portion on said link, and said stud member and said disc portion being of substantially the same diameter, and a beaded end on said link member extending into the opening in said button for covering the piercing point of said stud. 80

2. A sectional detachable button for garments comprising a stud member, a button member and an intermediate link portion, said link portion being formed to provide a spherical projection at one end thereof and projected portions on said stud members adapted for piercing and holding the material to which said button is attached, and said stud having an enlarged central threaded portion for engagement with said link portion. 90

3. A detachable button for garments comprising a stud member having formed integral therewith a plate portion, and a piercing point, said plate portion being provided with upstanding prong members, a link adapted to be attached to said stud portion, and having a spherical receptacle into which the piercing point of said plate extends said link being provided with a flange, the outer periphery of which is knurled, a button removably associated with said link members and the outer periphery of said button and said stud plate portion being knurled, and the plate portion, the flange portion and the bottom of the button being of substantially 100 the same diameter. 110

4. A detachable button comprising a stud shank having a central enlarged threaded portion and a piercing point, a stud plate 115 formed integral with the stud shank and provided with piercing points, a link having an intermediate button receiving portion and an enlarged end adapted to form a center for said button when the same is in place on the link, and said link having a disc portion whereby the material to be held will be compressed between said disc portion and said stud plate. 120

5. A sectional button comprising a stud member, the upper end of which constitutes 125

a piercing point, said stud having a central, to be threaded on said link, said button being provided with a central opening for the reception of said link bead, and the bead, the ¹⁰ button and the link, being knurled on their outer periphery.

In testimony whereof I affix my signature.

GEORGE KELLOG. [L. S.]
